(57) **CLAIM**

The ornamental design for an applicator for applying material to a surface, as shown and described.

DESCRIPTION

FIG. 1 is an isometric or perspective view of our design for an applicator for applying material to a surface

FIG. 2 is a front view of the design shown in FIG. 1

FIG. 3 is a side view of the design shown in FIG. 1

FIG. 4 is a top view of the design shown in FIG. 1; and,

FIG. 5 is a bottom view of the design shown in FIG. 1.
